HIGH SPEED LOOM

Charles L. Kennedy, Columbia, S. C.

Application January 25, 1933, Serial No. 653,511
Renewed January 15, 1938

29 Claims. (Cl. 139—145)

This invention relates to looms and has for its principal object the provision of a picker mechanism having a capability of much higher speed than the present stick driven pickers.

5 A further object of the invention is to provide a picker mechanism which will be little affected by changes in humidity and which will require minimum power.

A still further object of the invention is to provide 10 a picker mechanism which can be readily added to any existing lay as a unit and requiring very little changes in the existing mechanism. Still further objects of the invention relate particularly to refinements tending to smooth the 15 operation, insurance that the shuttle will always be in one or the other of the two boxes whenever the machine is stopped for any cause, the bringing to rest of the shuttle and of the picker mechanism with an absence of rebound and positive withdrawal of the binder prior to discharge 20 of the shuttle.

The modern loom operates up to speeds of approximately 165 picks a minute but the tendency is now, and has been for some while past, toward 25 the increase of this speed and experimental machines have been driven over 200 picks per minute but apparently the mechanisms which are capable of this speed are unsatisfactory because of their short life and the excessive wear on the 30 loom driving mechanism and the picker mechanism itself. The picker stick seems ideal for lower speeds but as the speed increases a point is reached short of the speed desired at which the picker stick seems to be incapable of possessing 35 the proper resilience to give smooth action and as a natural consequence the replacements become excessive. In the present device the picker stick is entirely eliminated and is replaced by a metal picker arm of quite short length, the arm 40 being substantially free, that is, it has no pivoting and at the time of discharge is rocking against a single element and is otherwise free with a natural consequence that the action is smooth during the giving of the principal force of the 45 blow. The spring which drives the picker arm is likewise quite free of the other mechanisms having no precise pivot altho constrained to move in a path to yield maximum efficiency and to give a smooth coming to rest in both loading and 50 discharge. By making the spring barrel and the picker arm substantially free and by replacing the normal pivotal action by a rocking action, it is possible to discharge the shuttle at a speed greater than the present loom mechanisms can 55 take care of and by lowering the power of the

spring it is possible to suit the picker mechanism to any chosen speed.

In the drawings—

Figure 1 is an end elevation of a loom showing only such part of the mechanism as is necessary 5 for understanding the present invention.

Figure 2 is a top plan view looking down on the lay.

Figure 3 is a front elevation.

Figure 4 is a front elevation, partly in section, 10 showing the picker mechanism just prior to receiving the shuttle.

Figures 5 and 6 are front elevations showing respectively the positions of the parts at the moments of cocking, and of loading the mechanism. 15

Figure 7 is a plan view of the mechanism shown in Figure 4.

Figure 8 is a detail view of the trigger and trigger lever assembled with the binder release trigger fingers.

Figures 9 and 10 are detail views showing the 20 way in which the main lever of the shuttle throwing mechanism is connected to the connecting rod.

Referring particularly to Figure 1, the frame 25 10 is of standard construction having the usual feet 11 by means of which the frame is fastened to the floor, and a countershaft 12 driven from the main shaft located above but not shown for clearness of illustration. The lay 15 rocks about 30 the pivot 16 and carries the picker mechanism forming the invention.

On the countershaft 12 the usual stick driving cam is removed and for it is substituted a cam 17 of special design driving a roller 18 on 35 the vertical leg 19 of a bell crank lever pivoted as at 20 to a bracket 21 which is secured to the curved portion of the frame shown. The horizontal leg 22 of the bell crank lever extends forwardly on the outside of the frame while the vertical leg 19 is on the inside of the frame as illustrated in order to be in position to engage the cam 17, the latter furnishing all of the power for the picker mechanism comprising the present invention except for the very slight movement 45 needed to cock the picker arm, such movement being provided by the moving shuttle at the end of its travel.

The lay 15 on the replenishing end, which is the end shown, has the usual slot 25 to the back 50 wall of which is secured the supporting plate 26 which carries substantially all of the present mechanism, the exceptions being the mechanism heretofore described and the connecting rod 28 which joins the free end of bell crank lever 22 55

with the free end of what will hereafter be called the main lever numbered 30. As will be noted in Figure 2, the picker head 31 projects upwardly thru the slot 25 coaxial with the axis of the shuttle 33 which is driven from end to end of the lay by the picker mechanism and is frictionally received in each end or box by the usual binder 35 of well known and old type pivoted as at 36 in an adjustable bracket 37. The binder 35 is controlled in the usual way by an adjustable spring 38 on the protection or safety rod 39, the latter carrying an upwardly extending arm 40 bearing against the free end of the binder 35 so as to press the binder yieldingly against the shuttle 15 which at such time will be in firm engagement with the oppositely positioned stationary guide 41 forming the rear wall of the so-called box.

The parts just described are all old and well known, the new feature being that a lever 43 is pivoted as at 44 to a bracket 45 preferably secured to the lay by means of one of the usual bolts 46 which secure the standard bracket 47 in place, the latter furnishing a bearing for the safety rod 39. The lever 43 is centrally pivoted 25 in a leather bearing 49 secured to the binder about centrally as, for example, by the screws 50'. Any other type of pivot may be used at this point but the leather bearing appears to be very advantageous as it is so little affected by the necessary jars that the binder suffers. Toward the free end of the lay and the pivot end of the binder the lever 43 ends in a lug 51' lying in the path of the two trigger fingers 54' and 55'.

The main lever 30 is one arm of a three-armed bell crank lever pivoted to the plate as at 50 and serving to compress the firing spring and to operate a latch or trigger which will release the picker arm so that the latter can discharge the shuttle across the lay. This action is accomplished thru a very important element of the invention which for lack of a better term will be denoted the barrel lever, this element, numbered 51, being pivoted to the frame as at 52 and having an adjustable link connection with the outer 45 arm 53 of the bell crank lever including the main lever 30 the connection preferably including a toggle mechanism which, as illustrated, includes a socket rod 54 having a ball 55 receivable in an adjustable socket 56 carried by the barrel lever 50 and a similar ball receivable in a stationary socket 57 carried by the free end of the lever 53, the arrangement being such that when the end of the main lever 30 is at the lower limit of its travel the toggle formed of the socket rod 54 and the lever arm 53 will be in straight line position. A spring such as 59 constantly urges the barrel lever 51 to position to raise the free end of the main lever 30 and this urge thru the connecting rod 28 and lever 19 holds the roller 18 at all times 60 in firm contact with the driving cam 17. I find it convenient to employ an additional spring 61 coiled about the pivot 20 to aid in the holding of the roller 18 against its cam 17.

At the upper end the barrel lever 51 carries a pin 60 projecting thru a slot 62 in a curved heel 63 forming the bottom or end of the spring barrel 64, this pin 60 forming the sole support for the barrel. Within the barrel is a relatively heavy helical spring 66 mounted on a rod 67 threaded thru a spring seat washer 68 and having at the other end a hexagonal head 70 by means of which the tension on the spring 66 can be adjusted. A knife edge 71 is carried by the rod 67 and engages a notch 72 in the picker arm 73. The spring 66 is always under tension and con-

sequently holds in assembled relation the spring 68, the barrel 64, the barrel lever 51 and the picker arm 73, there being a slot 75 in the barrel lever thru which the spring rod 67 passes.

In bearings 77 and 78 rising from the plate 26 5 is a trigger shaft 79 carrying a curved latch or trigger plate 80, the function of which is to hold and to release the picker arm 73, the trigger being urged to latch position by means of a spring 81 the free end of which bears against 10 the wall of the lay slot 25. The spring 81 is fairly heavy and in addition to holding the latch against the picker arm and ready to cock the picker it also serves to add considerable friction to the binder 35, accomplishing this purpose by means 15 of the finger 54' which bears against the flattened end 51' of the lever 43 serving to add considerable pressure to the binder whenever the latch is released. Until the latch is released however there is no pressure whatsoever against the end 20 51' of the lever 43 because the trigger or latch 80 at such time is resting firmly against the picker arm and the lever 43 is consequently free of pressure from the finger 54', the latter always moving with the trigger 80.

Also mounted on the trigger shaft 79 but moving entirely independently of the trigger 80 and the finger 54' is a bell crank lever, the vertical arm of which carries the finger 55' and the horizontal arm 84 having an adjustable connection 30 such as 85 with a link 86 the lower end of which preferably carries a stud 86' (see Fig. 8) which stud is guided in a slot 87 and the head of which is engaged and moved downwardly by the lever 88 which is the third arm of the bell crank lever 35 pivoted at 50, the other two arms being the main lever 30 and the toggle lever 53. A light spring 89 may be used to keep the horizontal arm 84 elevated in order to prevent the finger 55' from resting against the lever 43 which operates the 40 binder in order to obviate the formation of slack.

The picker arm at its lower end has a knife edge 90 adapted to rest in a notch 91 at the bottom of the barrel lever 51 when the picker arm is in firing position, that is, just prior to discharge of the shuttle. The primary function of this knife and notch connection is to insure that the picker head is at a definite level prior to each blow and the connection is broken instantly upon firing. At the time of firing the only connection 50 of any kind between the picker arm and the barrel lever is thru the knife edge 90 but immediately upon initiating the shuttle discharge action the picker arm rolls on the barrel lever, the proximate edge 92 of the picker arm being 55 plane while the adjacent edge 93 of the barrel lever is curved on an arc struck from a center beyond the spring but in its axis. This arcuate form is highly advantageous as it eliminates jars and serves to dampen the action at the end of 60 the strokes. There is a very similar action between the plane face 94 on the barrel lever and the contacting arc 95 at the bottom of the barrel 64, this arc also being struck from a point in the axis of the spring but beyond the spring. 65

The picker arm is preferably forked so that the toggle lever 53, the socket rod 54, and the rod 67 can all pass centrally thru the picker arm, this giving a considerably better action and allowing the knife 71 to have an extended bearing. I 70 prefer to have the knife 71 in the simple form shown as it is so much more compact than forming this knife of U-shape, the advantage of the latter of course being that the operative edge is nearer the junction between the barrel lever and 75

the picker arm. The simple form illustrated appears to have practically the same advantages however because the slot 75 in the barrel lever is of very slight extent in either event. The particular picker head illustrated is quite advantageous. In this the cup 96 instead of carrying the leather carries a solid rubber cushion 97 at the forward end of which is a metal ferrule 98 in which is mounted the usual leather 99 which rests firmly against the solid rubber connection. The advantage of the rubber is that by having this rubber as shown wear on the shuttle point is eliminated in case of inaccuracy in binder adjustment, the rubber readily yielding to take care of any reasonable irregularity. The leather however is seemingly necessary as it takes the wear very nicely and this the rubber seems unable to do. The resiliency of the rubber in addition seems to add materially to the speed of the throw of a shuttle, the leather having practically no resilience.

In applying my unit to an existing machine the picker head, being larger in diameter than the usual slot in the lay, is removed merely by taking off the single nut 100 and the unit is inserted in the slot by lifting the unit up into place and the base plate 26 is then secured to the wood of the lay 15 by the simple screws 101. The picker head may now be secured in place and should be adjusted so as to be very accurately centered, this being facilitated by the fact that the holding bolt 102 which rests against the metal cup 96 is a bit smaller in diameter than the hole in the base of the metal cup and is also appreciably smaller in diameter than the hole 104 in the end of the picker arm 73. Once put in place, however, this adjustment is complete and in fact no adjustment whatsoever of the unit is necessary in taking it off and replacing it on a definite loom except for the tightening of the spring by means of the head 70. The usual cam on the countershaft 12 is removed and replaced by the cam 17. The bell crank lever is installed on the bracket 21, which usually must be added, and then the bell crank arm 22 is connected to the bell crank arm 30, which is the main lever, by means of the connecting rod 28 which may be of any desired form but which conveniently consists of a member having at each end a knife edge 105 integrally secured to a U-member 106 having laterally extending lugs 107 and also having a tubular portion 108 tapped to receive the threaded ends 109 of the rod 28. The lever arm, whether 30 or 22, is received within the U portion 106 and may conveniently be detachably secured thereto by a simple U spring such as 110, the base or connecting portion 111 resting upon the rod such as 30, then passing beneath pins 112 on the rod and the free ends resting upon the two lugs 107 which may be slightly curved to receive them altho this is not necessary because the natural springiness of the wire will hold these in place and the free ends of the wire will of course, press the knife edge 105 firmly against the notch in the arm such as 30. The length of the connecting arm is adjusted so as to be tight when the main lever 30 is at the end of its stroke, the toggle is straight and the action of the roller 18 is at its most distant point from the axis of the countershaft 12, that is, when the cam 17 is at its extreme throw. The main spring 66 is now tightened to a chosen strength which will always be appreciable and which will vary with the speed desired, that is, the spring should be tightened to a greater extent as the speed of the loom is increased. The

next adjustment is to set the nut 85 which rests against the manually operable finger release portion 84, this being a horizontal arm of the bell crank lever. This adjustment should be so made that the toggle 53—54 is straight the trigger 80 5 is just free of the picker arm 73. This adjustment once made need never be altered as the cross actions of the trigger and picker arm give no opportunity for wear. In other words the transverse action of the trigger with respect to 10 the picker arm keeps the rubbing surfaces at all times sharp.

The action of the device is as follows starting with the shuttle at the far end of the lay: At such time the picker head is at a point just short of 15 its rearward travel and the trigger or latch 80 is resting against the side of the picker arm, the latter preventing the trigger from operating. The finger 54', moving at all times with the trigger, is entirely free of the binder operating lever 20 43 which latter is at this time spaced somewhat from the opposite finger 55' this being due to the presence of the spring 89. The free end of the main lever 30 is elevated and the main spring 66 is holding the spring barrel 64 against the 25 barrel lever 51 and also holding the barrel lever against the picker arm 73. The spring 66 is aided in such action by the strong but relatively much weaker spring 59 which preferably circles the pivot 52 bearing against a pin 115 on the 30 spring lever and against a stationary stop 116 rising from the plate. At this time the sole contact between the picker arm and between the barrel lever and the spring barrel is in line with the rod 67. The spring barrel 64 in turn is 35 pressing heavily against the upper guide 120 and entirely free of the lower guide 121, both of these guides being surfaced with leather or similar material. The spring 81 holds the trigger 80 quite firmly against the picker arm but at this 40 time has no other effect. The shuttle is now thrown by the opposite picker mechanism thru the shed and toward the uncocked picker head. When the shuttle reaches the box the binder acts thru the already existing or prior mechanism 45 and practically brings the shuttle to rest in the desired position but the adjustment of spring 38 is purposely made just a bit weaker than usual in order to insure that the shuttle shall reach the picker head with sufficient momentum to 50 give a slight blow to the leather cup 99, sufficient to drive the picker head back the very slight distance required to cock the picker head, that is, to permit the trigger 80 under urge of its spring 81 to snap into place and perform two 55 simultaneous functions, one to lock the picker head in rearmost position and the other to apply an additional force to the binder 35 thru the lever 43, this sudden additional pressure on the binder making a very positive lock for the 60 shuttle and preventing any rebound of that member. The tendency of the picker head is to move still farther back and to rebound but this tendency is completely damped out by the fact that while the spring barrel can move rearwardly 65 with the upper ends of the barrel lever 51 and the picker arm 73, the leather lining of the upper guide 120 severely resists this movement and absolutely bars any rebound. The shuttle has previously been locked into position and while 70 the picker head moves slightly back of the locked position of the shuttle, the picker head moves forward under the urge of the very heavy spring 66 at a slow rate, the snubbing action of the guide 120 not being sufficient to bar action 75

while absolutely preventing any rapid movement of the barrel and consequently of the picker head. The harness now acts to reverse the shed, the reeds now operate, and the mechanism is in 5 readiness to start its cycle, beginning with the lowering of the outer end of the main lever 30 by means of the cam 17. Such movement causes the descent of the three connected levers 30, 53 and 88. The barrel 64 and the therein contained 10 main spring 66 move forwardly with the retaining washer 68 moving somewhat downwardly. The barrel lever 51 turns about its pivot 52 under the urge of the toggle 53—54 and rocks against the arcuate surface 95 of the spring barrel, thus 15 compressing the spring 66 since the head 70 is held against movement by its contact with the picker arm which remains stationary during the loading of the spring. This action continues while the toggle straightens at which time the spring 66 is fully loaded. The descent of the 20 third lever 88 has no effect until the finger 55 has engaged the end of the binder operating lever 43 but when the end of this lever is in firm contact with both of the fingers 54 and 55' it 25 is moved so as to release the binder completely from the shuttle and this act takes place just prior to the firing of the picker arm by the withdrawal of the trigger 80. The picker head snaps forward sharply as the spring 66 is released. The 30 spring barrel 64 due to its rocking as the barrel lever 51 moves forwardly, is in very firm contact with the lower guide 121 and this frictional engagement prevents recoil as the greater the pressure on the guide 121 the greater the friction. 35 Consequently as the picker head thus moves sharply forward the point of engagement between the arc 95 and the straight edge 94 on the barrel lever and similarly the point of contact between the arc 93 on the barrel lever and the 40 straight face 92 of the picker arm are both appreciably above the level of the rod 67 forming a gap between these three parts at the level of the rod 67. There is no slap action at all because both parts roll on the adjacent surfaces. 45 However, as the picker head moves forward this rolling causes the head 70 on the rod 67 to move upwardly and the two arcs cause an increase of the distance between the head 70 and the spring seat 68, thus compressing the spring. 50 Such compression resists powerfully further forward movement of the picker head and the guide 121 also adds its effect to the snubbing action because the further compression of the spring 66 increases greatly the friction of the barrel 64 against the guide 121. The compression of 55 the spring 66 at the end of the stroke causes tendency of the parts to return and this tendency is resisted strongly at first by the friction of the barrel against the bottom guide. Inasmuch as the barrel rises on return stroke this 60 friction is very rapidly eliminated and the parts are then under the sole urge of the spring 59 and the backward movement of the barrel causes the barrel to rise against the guide 120 so that the friction between the barrel and the upper guide 65 snubs the return movement so that there is scarcely any rocking engagement between the barrel lever 51 and the picker arm or barrel bottom 95 below the axis of the spring. The parts 70 are therefore brought to rest with a very smooth rocking action which takes place with extreme rapidity and without any jar whatsoever.

What I claim is:

1. In a spring discharge mechanism, a discharge member, a pivoted lever, a spring seat

having a cylindrical face resting against said pivoted lever, a spring pressing against said spring seat, means engaging said discharge mechanism and the free end of said spring, means for moving said pivoted lever to compress the spring and trigger mechanism for releasing the discharge member, whereby upon release of the discharge member the pivoted lever will have rolling action with the spring seat. 5

2. In a picker mechanism, a picker arm, a pivoted lever having rolling contact with the picker arm, a spring, trigger means for holding the picker arm and means engaging said picker arm while so held for compressing said spring. 10

3. In a picker mechanism, in combination, a pivoted lever, a spring seat having a cylindrical face engaging said lever, a spring engaging said seat, a picker arm having rolling contact with the pivoted lever, and means connecting the free end of the spring with the picker arm. 15

4. In a spring discharge mechanism, a pivoted member, a spring barrel engaging said member, a spring within said barrel, means for moving the pivoted member about its pivot to compress the spring within the barrel and a recoil damping mechanism including a friction element in the path of the barrel as it moves with said pivoted member. 20

5. In combination, a pivoted lever, a spring resting against said lever and movable with said lever about the pivot of the lever, means for holding the free end of the spring, means for moving the lever about its pivot to compress the spring and snubbing means located on opposite sides of said spring for damping recoil of the 35 spring. 30

6. In a picker mechanism, a lay, a supporting member secured to said lay, a bell crank lever pivoted on said supporting member, a picker arm, a spring for operating said picker arm and a link forming with one arm of said bell crank lever a toggle positioned so that when the spring is fully loaded by movement of the toggle the toggle is in straight line position whereby there is no tendency of the other arm of the bell 45 crank lever to move about its axis at the moment the picker arm is discharged by its springs. 40

7. A picker arm for a high speed loom comprising an elongated member having means at one end for carrying a picker, fulcrum means at 50 the opposite end, said member having a slot down its middle portion, and having a smooth bearing surface on one side normal to said slot, and a fulcrum means on the opposite side. 55

8. In a high speed loom having a lay, a picker mechanism comprising a lever member pivoted on said lay, and a picker carrying member on one side of and carried by said lever member said members being spring pressed together and having rolling engagement with each other. 60

9. The device of claim 8 in which one of said members has a convex surface whereby one member may roll on the other. 65

10. In a high speed loom, a slotted lever having bearing surfaces on opposite sides, a shoe 65 carried by the lever and having a curved surface bearing against the bearing surface on one side of the lever, a slotted picker arm carried by the lever and bearing against the bearing surface on the other side of said lever, and spring pressed retaining means passing thru the shoe, the lever and the arm whereby the lever is compressed between the shoe and the arm and whereby the arm and the lever are normally held in a 70 75

- predetermined relative position to which they return after each disturbance of the picker arm caused by throwing and receiving the shuttle.
11. In a picker mechanism, a picker arm having on one side an elongated bearing surface, a pivoted lever having a smooth bearing surface for engaging the bearing surface of the arm, one of said surfaces being curved whereby the arm may roll on the lever, spring means for causing the arm and lever normally to engage on a predetermined line transverse of the curved surface and for resisting said rolling action and the separation of the arm and lever and means for separating the arm and lever against the action of the spring means.
12. In a picker mechanism, a compound picker arm comprising two substantially parallel links, spring means for yieldingly holding said links together, one of the links being pivoted at one end and adapted to oscillate thru an arc between a forward and rearward limit, the other link being carried by the first mentioned link and having at one end an open fulcrum connection with the first mentioned link and at the other end means for supporting a picker, means for latching the picker carrying link at the rearward limit, means for moving the pivoted link to its forward limit thereby storing energy in said spring means, and means for releasing the latching means upon the pivoted link reaching its forward limit, said links having rolling engagement one with the other whereby eliminating impact.
13. In a loom, a pivoted arm, a picker arm arranged to rock on said pivoted arm, a spring connected to resist relative movement of said arms, a trigger for holding one of the arms stationary, means for moving the other arm to store shuttle discharge power in said spring, and means operated by said arm moving means for operating the trigger to release the stationary arm whereby the picker arm is discharged.
14. In a loom, shuttle discharge mechanism including a spring pressed picker arm, locking means for holding said arm against movement during loading of the spring, mechanism for storing energy in the spring to load the same while the arm is so held against movement, means for at will moving the locking means out of arm holding position to prevent loading of the spring whereby permitting adjustments in the loom shed without any fear of discharge of the shuttle.
15. In a loom, a lay, a shuttle discharge mechanism carried by said lay including a spring pressed picker arm, a main lever, a barrel lever for compressing said spring, linkage connecting said main lever to the barrel lever, said linkage including a toggle joint connected to and actuated by the main lever to straight line position to compress the spring, at which position the spring is fully loaded, whereby upon release of the picker arm to discharge the shuttle the main lever is under no urge to rotate about its pivot.
16. In a picker mechanism, a lever pivoted to oscillate on a fixed axis, a picker arm, and means including a spring for holding the picker arm against the lever to thus form the sole support for the picker arm and cause the arm to oscillate therewith in its shuttle discharge operations.
17. In a loom, a picker arm, a spring for discharging said picker arm, means connecting said spring and said picker arm, said means being movable with the spring and also movable with the picker arm, a pivoted lever engaging said spring and having rolling engagement with the picker arm and cooperating with said connecting means to form the sole support for the picker arm.
18. In a loom, a lever, a picker arm supported on the lever and having rolling engagement therewith, a spring pressing the arm and lever together, means connecting the free end of the spring with the picker arm, means for holding the picker arm and means for moving the lever when the picker arm is so held thereby to store energy in the spring for discharging the picker arm.
19. In a loom, a support pivoted to oscillate adjacent the shuttle box, a picker arm carried by the support and having rolling engagement therewith and spring means tending to constrain the arm to move with the support in a shuttle operating path.
20. In a picker mechanism, a picker arm, a picker arm support, said support and arm having rocking engagement whereby the arm may rock a limited amount in the support, spring means for causing the arm and support normally to contact on a predetermined line across the engaging surfaces and for resisting said rocking action and resisting the separation of the arm and support at the line of contact and means for causing said rocking action from said line of contact to store shuttle discharge energy in the spring means.
21. In a loom, a lay, a binder at one end of the lay, a spring for urging the binder against the shuttle, a spring pressed picker, a trigger for the picker, and spring means operatively connected to the trigger for exerting additional pressure on the binder at the moment the trigger moves into cocking position.
22. In a spring actuated discharge mechanism, a pivoted lever, a spring bearing at one end against said lever, a discharge mechanism bearing against the opposite side of said lever, a rod bearing at one end against the far end of the spring and bearing at the other end against the discharge mechanism, a trigger for holding the discharge mechanism, means for moving the pivoted lever away from the trigger held discharge mechanism and toward the far end of the spring to load the spring, and means for releasing the trigger to cause the discharge mechanism to move toward the spring lever.
23. A spring discharge mechanism including a picker arm and a supporting arm therefor, said arms having rolling engagement, a spring pressing against one of the arms at one side, a rod passing axially thru the spring and having a retaining member at either end one retaining member bearing against the far end of the spring and the other retaining member bearing against the other arm, said spring and said rod with the retaining members serving normally to clamp the arms together in a predetermined position whereby when the arms are rolled to a different relative position picker discharge energy is stored in the spring.
24. A picker mechanism unit for attachment to a lay of usual construction, consisting of a base readily removable from the lay, a spring lever pivoted to said base, a spring resting against said lever, a picker arm adapted to project through the slot of the lay and having a head substantially in line with the axis of the shed, said picker arm having rolling contact with said lever, a rod operatively connecting the free end of the spring with the picker arm, a trigger pivoted to said base, and means pivoted to said

base to load said spring and to release said trigger.

25. In a shuttle driving and receiving mechanism, a picker head, means for driving said head to discharge a shuttle, said means including a spring for returning the head to shuttle discharging position after each discharge action, a latch for locking the head in said position during loading of the spring, means normally holding the latch out of locking engagement, a shuttle binder, means urging the binder inward to resist and slow down the movement of the shuttle as the shuttle approaches the picker head, and means cooperating with the latch for increasing the binder pressure on the shuttle upon movement of said latch to locking engagement.

26. In a loom, a lay adapted to receive a shuttle, a picker and supporting means therefor, a spring for actuating the supporting means to discharge the shuttle from a predetermined position on the lay, a trigger adapted to lock said picker supporting means in said position during loading of the spring, spring means for returning said supporting means to a point just short of said position after each discharge of the shuttle, at which point said supporting means holds the trigger in non-locking engagement and means to discharge the shuttle against the picker to cause the picker supporting means to move to said position and into locking engagement with said trigger, whereby the trigger remains uncocked until the shuttle strikes the picker thus preventing loading of the spring in case the shuttle fails to strike the picker.

27. A spring actuated shuttle discharge mechanism comprising a picker arm support having

an elongated bearing surface, a picker arm carried by the support and having a cooperating surface, one of said surfaces being cylindrical thereby providing rolling engagement of the arm with the support and spring means pressing the arm against the support, and tending to hold the arm and support in a predetermined relative position and whereby movement to a different relative position stores shuttle discharge energy in the spring.

28. A shuttle discharge mechanism for looms comprising a supporting arm having a bearing surface along a substantial portion of its length, a picker arm, yielding means pressing the picker arm against the supporting arm, the engaging surfaces of the arms being smooth bearing surfaces, one of said surfaces being cylindrical whereby the yielding pressure causes the picker arm to roll to a predetermined position on the supporting arm, means for moving the arms to a different relative position thereby to store picker discharge energy in said yielding means.

29. A shuttle discharge mechanism for looms comprising a lever, means for mounting the lever to oscillate through a limited arc, a picker arm carried by the lever, energy storing means yieldingly holding the picker arm on the lever so that the arm when unrestrained oscillates with the lever about the axis of the arc, releasable means for locking the picker arm against movement from one limit of said arc, means for moving the lever from said limit to store energy in the storing means while the arm is so held and means for releasing the locking means thereby to permit the arm to snap forward under action of the energy storing means.

CHARLES L. KENNEDY.
